DESIGN FOR A COOKY

Jasper B. Carr, Trucksville, Pa., assignor to J. B. Carr Biscuit Company, Wilkes-Barre, Pa., a corporation of Pennsylvania

Application January 9, 1946, Serial No. 125,368

Term of patent 7 years

(Cl. D8—1)

To all whom it may concern:

Be it known that I, Jasper B. Carr, a citizen of the United States, residing at Trucksville, in the county of Luzerne and State of Pennsylvania, have invented a new, original, and ornamental Design for a Cooky, of which the following is a specification, reference being had to the accompanying drawing, forming a part thereof.

Figure 1 is a view in plan of a cooky embodying my new design, the opposite or back face being plain; and

I claim:

The ornamental design for a cooky, substantially as shown and described.

JASPER B. CARR.
